UNITED STATES PATENT OFFICE

121,920

DESIGN FOR AN ASH RECEPTACLE

Maurice J. Fletcher, Des Moines, Iowa, assignor to Talbert M. Dick, as trustee for Cadet Smokestands Company, Des Moines, Iowa, a common-law trust

Application December 4, 1939, Serial No. 88,665

Term of patent 14 years

To all whom it may concern:

Be it known that I, Maurice J. Fletcher, a citizen of the United States, resident of Des Moines, Polk County, Iowa, have invented a new, original, and ornamental Design for an Ash Receptacle, of which the following is a specification, reference being had to the accompanying drawing, forming a part thereof.

Fig. 1 is a side elevational view of the ash receptacle showing my design.

Fig. 2 is a top plan view thereof.

I claim:

The ornamental design for an ash receptacle, substantially as shown.

MAURICE J. FLETCHER.
